CLAIM

The ornamental design for a thermoelectric smartwatch, as shown and described.

DESCRIPTION

FIG. 1 is a top perspective view of a thermoelectric smartwatch in accordance with the present design;

FIG. 2 is a front view of the thermoelectric smartwatch;

FIG. 3 is a back view of the thermoelectric smartwatch;

FIG. 4 is a right side view of the thermoelectric smartwatch;

FIG. 5 is a left side view of the thermoelectric smartwatch;

FIG. 6 is a top view of the thermoelectric smartwatch; and,

FIG. 7 is a bottom view of the thermoelectric smartwatch.

The broken lines shown in FIGS. 1-7 in the drawings depict portions of the thermoelectric smartwatch that form no part of the claimed design.
